UNITED STATES PATENT OFFICE.

ROBERT H. HANNEMANN, OF WAUSAU, WISCONSIN.

RAILWAY-SWITCH.

1,244,849.

Specification of Letters Patent. Patented Oct. 30, 1917.

Application filed July 29, 1914. Serial No. 853,890.

To all whom it may concern:

Be it known that I, ROBERT H. HANNEMANN, a citizen of the United States, residing at Wausau, in the county of Marathon, State 5 of Wisconsin, have invented certain new and useful Improvements in Railway-Switches; and I do hereby declare the following to be a full, clear, and exact description of the invention, such as will enable others skilled 10 in the art to which it appertains to make and use the same.

This invention relates to railroads and has special reference to a railroad switch of the type which is controlled at the will of 15 the engineer operating a train.

The principal object of the invention is to provide an improved railroad switch of this description which will be sure in operation, cannot get out of order accidentally, 20 and cannot be tampered with by unauthorized persons.

Another object of the invention is to improve the track devices used in connection with said switches.

25 A third object of the invention is to provide an improved form of controlling device arranged to be carried on the locomotive and used in connection with the improved track devices.

30 With the above and other objects in view the invention consists in general of certain novel details of construction and combination of parts hereinafter fully described, illustrated in the accompanying drawings, 35 and specifically claimed.

In the accompanying drawings, like characters of reference indicate like parts in the several views, and:—

Figure 1 is a plan view of the track device. 40 Fig. 1^a is a similar view of the track device, the covers being removed therefrom.

Fig. 2 is a transverse section through such a device showing the covers, which are used to protect the device from robbers or other 45 unauthorized persons, in position.

Fig. 3 is a longitudinal section through the track device.

Fig. 4 is a detail view of one of the operating levers or catchers for the track device.

50 Fig. 5 is a side elevation of the engine supported mechanism, the engine itself being shown partly in dotted lines.

Fig. 6 is a plan view of the engine supported mechanism.

55 Fig. 7 is a detail view partly in section and partly in elevation of a tubular rock

arm and plunger therefor, which carries the gripping device for operating the switch, certain adjacent parts being also shown.

Fig. 8 is a detail view showing a certain 60 safety device used in connection herewith, the view being in elevation.

In the accompanying drawings there is indicated a main line track consisting of the rails 10 and extending from this main 65 line track is a side track or turn out consisting of the rails 11. This turn out is provided with the usual switch point 12 where when the switch point is moved in one direction the cars will pass onto the turn out 70 while when the switch point is turned in the opposite direction the cars will continue on the main line track.

Slidably mounted in suitable bearings 13 is a transverse bar 14 whereon are keyed 75 certain sleeve members 15.

Slidable in each of these sleeve members is a rod 16, each of these rods 16 being provided with a collar 17 locked in adjusted position on the rod by a set screw. Thus 80 the cross bar has a slidable connection with the switch tongue. It is to be observed that this cross bar is cut away as at 19 to provide an opening or slot. Extending through this slot is a pair of cam members 20 which, 85 when in one position, serve to force the bar to the right and when in the other position serve to force the bar to the left. In order to permit this movement without too great shock on the switch tongue the springs 21 90 are provided which surround the rods 16 between the collar and the sleeve members so that the slidable connection before mentioned is resilient.

The cam members 20 are carried by a longitudinally movable bar 32 which slides in notches or bearings 22 and extends along the track between the rails to any suitable point as indicated in Fig. 1^a.

Adjacent each end of this bar 32 there is provided a suitable pit wherein is placed a foundation tie 24 having mounted thereon certain bearings 25 wherein works a crank shaft 26 to which is connected the upper end of a pair of springs 30, the other end of 100 each of said springs being connected to the foundation tie 24.

There is a crank shaft 26 for each of said rods 32 and each of said rods is provided with an elongated opening 32' in which its 110 respective crank shaft is adapted to operate in a manner to be hereinafter described.

Extending upward at an end of each of said crank shafts there is an operating arm 33 provided on its upper end with a catch engaging end 34. The pit wherein this 5 crank shaft works is provided with a cover 35 which extends transversely across the track and supported beneath this cover 35 are certain rollers 36 whereon work a segmental cylindrical plate 37 having a frustoconical opening 38 in its center wherethrough passes the member 33. It is to be understood that the plate 35 also has an opening in its center so that the member 33 can be moved backward and forward thus 10 carrying with it the closure plate 37 so that gravel and sand is prevented from dropping into the pit while at the same time said member can have free movement.

In order to protect the working parts 20 from robbers and the like certain I beams are employed whereon are secured doors as shown, these I beams being indicated at 40 and the doors shown at 41. These doors are hinged to the I beams 40 and overlap 25 at their meeting edges, and are adapted to be locked or secured together in any suitable manner, such as by the bolts 42, and these bolts may be of any preferable or special form, capable of being manipulated only by 30 means of special keys or wrenches.

Turning now to those parts of the device which are supported on the engine and which are shown in Figs. 5 to 8 inclusive. Attached to the engine is a suitable frame work which is indicated in general at 45. Mounted on this frame work is a steam cylinder 46 provided with the usual piston and the rod of which is shown at 48, the latter being supported in an outboard bearing carried by certain brackets of the frame as indicated at 49. This steam cylinder is provided with certain inlet pipes 50 at each end thereof and on the under side of the cylinder there are provided the outlet pipes 51. 35 These inlet pipes are controlled by suitable valves 52 and levers 53, these levers being connected by the link 54. The arrangement is such that when one of these valve is opened the other is closed. In like manner the valves to pipes 51 are provided with 40 a connecting link 55 so arranged that when one valve is open the other will be closed. These links 54 and 55 are connected by links 56 to a lever 57 pivoted to the frame and to 45 this lever is in turn connected a link 58 which has its remaining end connected to a latch lever 59 provided with the usual latch working over a quadrant 60. The arrangement of the links 56 and lever 57 is such that when taken in connection with the links 54 and 55, when said lever 57 is moved from its usual position, the inlet port at one end of the cylinder will be opened at the same time that the exhaust port at the other end 60 of the cylinder is opened. Thus the piston

can move from one end to the other of the cylinder under the influence of movement of said lever 57 to open and close said ports or valves.

Mounted on the frame 45 is a bearing 61 70 wherein is journaled a rock shaft 62 carrying on one end a rock arm 63 which passes upward through a collar 64, said collar being rotatably mounted on certain pivots and located in a slot 65 formed in the piston rod 48, the pivots being indicated as set screws 66. The other end of this rock shaft 62 is provided with a tubular rock arm 67 wherein is mounted a plunger 68, said rock arm having a head 69 in its lower end wherethrough 75 passes the piston rod 70 of said plunger or piston 68. Between the plunger 68 and the head 69 is held a coiled spring 71 which normally urges said head upward in said rod. On the lower end of the piston rod 70 is 80 mounted a gripping device 72 which is arranged, when properly positioned, to engage the knob 34 and pull the lever 33 open to operate the switch. By reason of the spring arrangement in the hollow rock arm 85 90 this engagement will be yieldably made so as to prevent damage to any of the parts.

Furthermore depending from the frame 45 are certain frame members or supports 74 whereto are pivoted arcuate arms 75, 95 the free ends of which being normally drawn toward each other by means of a spring 76. These arcuate arms furthermore carry certain gripper jaws 77 which are arranged to swing away from each other when the arms 100 are forced apart and to swing toward each other when the arms are drawn together. On the member 56 is a pair of spaced conical wedges 78 which are arranged to selectively engage the aperture between respective pairs of arms 75 so that by the movement of the rack 56 the gripper jaws 77 will be moved toward or away from each other. 105

It will be obvious that an ordinary target stand 79 may be employed in connection with this invention and this target stand may be connected to the switch operating bar by means of a link 80 so that as the switch is moved the proper position of the target will be indicated.

The operation of the device is as follows: Assuming that a train is approaching the switch from the right hand side of Figs. 1, and 1^a, it is apparent that it will be necessary to operate the trip member 34 to the right of said figures. To perform this operation the engineer operates the lever 59 to move the piston in the cylinder 46 to the left in Fig. 5, until the member 72 moves to a vertical position in which position its lower end will engage the trip 34. When the trip 34 is engaged by the member 72, it will be seen that the operating rod 32 will be moved to throw its respective cam member into engagement with the cut out portion 19 115 120 125 130

of the cross bar 15 to operate the switch thus permitting the train to enter the main line from the siding 11. When the member 34 has been operated and the switch moved, upon 5 the engagement of the member 72 with the member 34, said member 34 will return to its initial position under the influence of the springs 30, and this movement will take place without in any manner affecting the 10 position of the switch points by reason of the operating rod 32 being provided with the elongated eye 32'.

After this operation has taken place it will be seen that the switch will be left open to a 15 train approaching from the left, and if it is desired to continue on the main line, the operating member 34 to the left of Figs. 1 and 1^a is operated in the manner heretofore described. After the switch has been oper- 20 ated, the engineer throws the lever 59 to move the piston 65 in the cylinder 24 and this action moves the member 72 to either of its supporting elements 77 as desired by the engineer.

25 There has thus been provided a simple and efficient device of the kind described and of the character specified.

It will be obvious that many minor changes may be made in the form and construction of this invention without departing from the material principles thereof. It is not therefore desired to confine the invention to the exact form herein shown and described, but it is wished to include all 35 such as come properly within the scope claimed.

Having thus described the invention, what is claimed as new, is:—

1. In a device of the kind described, the 40 combination with a switch operating track

supported mechanism, of means carried by locomotives for actuating said mechanism, said means comprising a cylinder, inlet and outlet valves at each end of the cylinder, a piston 45 movable in said cylinder, a piston rod projecting from said cylinder, a collar pivotally carried by said rod to rock in a vertical plane, a rock shaft mounted beneath said rod, an arm fixed on said rock shaft and projecting through said collar, 50 and a track device engaging arm fixed on said rock shaft and resiliently extensible, and means under the control of an operative for opening and closing said valves selectively. 55

2. In a device of the kind described, the combination with a switch operating track supported mechanism, of means carried by locomotives for actuating said mechanism, said means comprising a cylinder, inlet and 60 outlet valves at each end of the cylinder, a piston movable in said cylinder, a piston rod projecting from said cylinder, a collar pivotally carried by said rod to rock in a vertical plane, a rock shaft mounted beneath 65 said rod, an arm fixed on said rock shaft and projecting through said collar, a track device engaging arm fixed on said rock shaft and resiliently extensible, means under the control of an operative for opening and closing 70 said valves selectively, and a safety device arranged to engage the last mentioned arm when in inoperative position.

In testimony whereof, I affix my signature, in the presence of two witnesses:

ROBERT H. HANNEMANN.
